UNITED STATES PATENT OFFICE.

CALEB S. EVANS, OF UNION CITY, INDIANA.

MAGAZINE-FIREARM.

SPECIFICATION forming part of Letters Patent No. 650,829, dated June 5, 1900.

Application filed October 7, 1898. Serial No. 692,919. (No model.)

To all whom it may concern:

Be it known that I, CALEB S. EVANS, a citizen of the United States, residing at Union City, in the county of Randolph and State of Indiana, have invented a new and useful Fire-arm, of which the following is a specification.

My invention relates to firearms, particularly fowling-pieces, and more especially to that class wherein the barrel is mounted to slide upon a fore-stock or extension of the stock to provide for loading at the breech and in which the spent or discharged cartridge is automatically ejected when the barrel is moved forward preparatory to reloading to facilitate loading and firing with rapidity.

One object of the invention is to secure such a sliding connection between the barrel and the frame, including the stock and fore-stock, as to insure the accurate movement of the barrel upon the frame and maintain the parts in a fixed relation against lateral and vertical vibration in all positions, to provide means for securely locking the barrel in its normal or operative position when the piece is loaded, and to provide improved means having exposed actuating devices within convenient reach of the trigger-guard and yet out of the way of the hand of the operator while manipulating the triggers for releasing the barrel, the operation of the releasing mechanism being accomplished without necessitating the removal of the gun from the shoulder of the sportsman.

A further object of the invention is to provide simple and efficient means for utilizing the forward movement of the barrel preparatory to reloading for cocking the hammers, whereby when the barrel is returned to its normal position the piece may be fired without further manipulation.

A further object of the invention is to provide simple means whereby the barrel may be dismounted from the frame or stock to facilitate cleaning and for the purpose of folding the piece compactly for transportation and storage.

A further object of the invention is to provide such a construction of firing mechanism, of which the hammers are adjusted to be cocked by the forward or breaking movement of the barrel, as to enable the cartridges to be placed in the chambers of the barrel, with

the hammers at rest or in their lowered positions.

A further object of the invention is to provide such a combination of devices for cocking a concealed hammer as to enable the operation to be performed without straining the mechanism of the frame and without requiring special effort upon the part of the operator in moving the barrel to its broken or open position.

A further object of the invention is to provide in a double-barreled fowling-piece of the class described means for cocking both hammers simultaneously, while allowing the independent operation thereof, and in this connection to provide means for returning the hammer-cocking devices to the normal position, with the cocking-lever out of the path of the hammers, by the return of the barrel to its normal position.

A further object of the invention is to provide an extractor for engaging the shell of a spent cartridge by the movement of the firing-pin in discharging the cartridge, whereby in a double-barreled fowling-piece only the shell of that cartridge which has been discharged is ejected when the barrel is moved forward, and in this connection to provide means whereby the transverse resilience of the part by which the shell is engaged is utilized to eject the shell.

A further object of the invention is to provide simple and improved means for starting a cartridge as the barrel is moved forward whereby an unspent cartridge may be readily grasped by the sportsman when it is desired to unload the barrel.

A further object of the invention is to combine with the trigger a locking mechanism, constructed for actuation automatically when returning the parts to a normal position, so as to prevent a premature or accidental firing of the gun, said locking mechanism being adapted to be thrown into or out of operative position at the will of the user and a catch mechanism being employed to adapt the locking mechanism for automatic action or to throw it out of operation at will to admit of the gun being repeatedly fired without necessitating the releasing of the locking mechanism for each operation of loading and cocking the gun.

Further objects and advantages of this invention will appear in the following description, and the novel features thereof will be particularly pointed out in the appended claims.

In the drawings, Figure 1 is a side view of a fowling-piece constructed in accordance with my invention. Fig. 2 is a central longitudinal section of the operating mechanism of the fowling-piece, showing the adjacent portions of the stock and barrel, the latter being locked in its operative position. Figs. 3 and 4 are longitudinal sections of the barrel and adjacent parts to show, respectively, the normal position of the parts immediately after firing and the first step in the operation of advancing the barrel to eject the spent cartridge. Figs. 5 and 6 are side views to illustrate two other successive positions of the barrel and shell in the operation of ejecting the latter. Fig. 7 is a horizontal sectional view of the operating mechanism, taken in the plane of the lateral barrel-locking bolts and showing in plan the triggers, trigger-lock, and cooperating parts. Fig. 8 is a horizontal section taken in the plane of Fig. 7 looking upwardly. Fig. 9 is a transverse sectional view taken in the plane indicated by the line 9 9 of Fig. 2. Fig. 10 is a transverse sectional view taken in the plane indicated by the line 10 10 of Fig. 2. Fig. 11 is a detail view in perspective of the triggers, trigger-guard, and draw-plate operatively combined. Fig. 12 is a similar view of the trigger-guard detached. Fig. 13 is a similar view of the draw-plate detached. Fig. 14 is a detail view in perspective of the trigger-lock detached. Fig. 15 is a detail view in perspective of the traction-bar and hammer-cocking lever detached. Fig. 16 is a similar view of the barrel-unlocking slide detached. Fig. 17 is a similar view of the auxiliary or tongue-engaging barrel-locking bolt and operating devices. Fig. 18 is a similar view of the auxiliary tongue-engaging barrel-locking bolt detached. Fig. 19 is a similar view of the cartridge-starter detached. Fig. 20 is a similar view of the firing-pin and shell-ejector. Fig. 21 is a detail underneath perspective of the rear portion of the barrel to show the main locking-lug and the draw-plate actuator.

Similar numerals of reference indicate corresponding parts in all the figures of the drawings.

In the present embodiment of my invention the stock 1 is provided with a forward extension or fore-stock 2, upon which is mounted to slide a barrel 3, which may be of the double type, as shown, said barrel being provided with a central longitudinal depending rib 4 to fit in a longitudinal groove or way in the fore-stock, the cross-sectional construction of said rib being such as to provide an upper dovetailed portion 5 and a lower parallel-sided portion 6, said dovetailed portion fitting in and interlocking with a corresponding portion of the way in order to guide the bar-

rel accurately in its linear movement. The guide-rib 4 projects rearwardly beyond the extremity of the barrel to form a tapered and shouldered lug or projection 7, which underlaps the breech-block 8, secured to the stock, as in the ordinary practice, by means of an extension or tang 9. Disposed in transverse alinement in the fore-stock are lateral barrel-locking bolts 10, mounted in a suitable transverse guide 11, which intersects the way in which the rib 4 operates, and the inner ends of these locking-bolts are beveled forwardly to provide for their separation by the locking-lug 7 of the barrel-rib as the barrel is moved rearwardly to its normal or closed position, and said bolts are yieldingly held in position in front of and engaging the shoulders at the rear end of said locking-lug by means of actuating-springs 12, fitted in cavities 13 in opposite sides of the fore-stock and concealed by covering-plates 14, which serve to maintain said springs in their operative positions. Furthermore, the barrel is provided with a rearwardly-extending auxiliary locking-lug 15, which overlaps the breech-block to lie in a suitable seat formed in the upper side thereof and provided in its under side with a beveled notch 16 for the reception of the beveled upper end of an auxiliary barrel-locking bolt 17, said bolt being mounted for vertical movement or movement perpendicular to the plane of movement of the lateral bolts 10 and having a transverse slot 18, with which engages a transverse pin 19 on one arm of a bell-crank lever 20, mounted in the breech-block. The other arm of said lever depends vertically and is engaged by an actuating-spring 21, which serves to yieldingly hold the bolt 17 in its elevated or engaging position, whereby as the barrel is slid rearwardly the extremity of the auxiliary locking-lug 15 depresses the bolt 17, while the main locking-lug 7 represses the lateral bolts 10 to allow the subsequent engagement of the bolt 17 with the notch 16 and the bolts 10 with the shoulders of said lug 7 when the rear end of the barrel comes into contact with the breech-block. Also arranged in operative relation with the lateral barrel-locking bolts 10 is a barrel-unlocking slide 22, preferably slotted longitudinally, as shown at 23, for a purpose which will be understood as the nature of the invention is more fully disclosed, and which is provided with opposite beveled or cam faces 24, normally arranged in contact with the beveled engaging extremities of the bolts 10. This unlocking-slide is mounted for reciprocatory movement in the fore-stock, and by moving the same rearwardly from the position indicated in Fig. 7 it is obvious that the lateral bolts 10 will be repressed to disengage the shouldered lug 7, and said slide is also provided with a slot 25, into which projects the lower extremity of the depending arm of the bell-crank lever 20. Thus as the slide is moved rearwardly the lateral bolts 10 are compressed outwardly to

disengage the lug 7, while the bolt 17 is drawn downward, in opposition to the spring 21 to release the lug 15, and thus provide for the manual forward movement of the barrel.

5 The trigger-guard 26 is secured by means of its plate 27 to the under side of the stock, and mounted thereon to slide parallel with the length of the stock is a trip-plate or draw-plate 28, having at its forward end an upwardly-extending lug or finger 29, engaged with an elongated opening 30 in the unlocking-slide 22, and said trip-plate or draw-plate is yieldingly held in its normal position, with the slide 22 in position to allow the engagement of the lateral and auxiliary locking-bolts with the barrel by means of a spring 31, which may, as illustrated, be housed in a box 32, countersunk in the stock and carried by the trigger-plate, said trip-plate being provided with a projection or follower 33, operating in said box in contact with one end of the spring. The trip-plate is provided with front and rear ears 34 and 35, between which the fingers of the operator's trigger-hand may be arranged, whereby in using the fowling-piece said trip-plate may be positively actuated in each direction, said spring, however, serving to prevent accidental disengagement of said plate when manually released.

The fowling-piece illustrated in the drawings is of the double-barrel type, and hence a gun-lock is provided for each barrel, the same comprising a hammer 36, a main or hammer spring 37 terminally engaged with a notch in the hammer, a sear 38, a sear-spring 39, and a trigger 40, having a trigger-spring 41. The triggers are pivotally mounted upon an upward projection 42 from the trigger-plate, and the trigger-plate and draw-plate are provided with suitable registering slots, through which the triggers, the follower 33, and other parts, hereinafter described, extend to allow the free longitudinal movement of the draw-plate. The hammers are provided with inwardly-projecting cocking-pins 43, extending toward each other from the facing or inner surfaces of the hammers and arranged in the path of the upper portion of a cocking-lever 44, which is of the first order and pivotally mounted upon a fixed bracket 45, projecting rearwardly from the breech-block into the cavity of the stock, said cocking-lever being common to the two hammers and being indicated in detail in Fig. 15. The cocking-lever is preferably bifurcated, as shown, to provide parallel arms arranged upon opposite sides of the plane of the bracket 45, and the fulcrum 46 of said lever is alined with the fulcrums 47 of the hammers. The interval between the cocking-pin 43 and the fulcrum of each hammer is small, and hence the leverage in moving the lower extremity of the cocking-lever forwardly is sufficient to overcome the tension of the mainspring with little effort on the part of the operator, my object in using a lever of the type described—

namely, of the first order—being to secure this coaxial mounting of the lever and the hammers and avoid a sliding contact between 70 said-lever and the cocking-pins during the cocking of the hammers.

Depending from the barrel to operate in the above-described longitudinal way in the fore-stock is a traction-plate actuator of sectional construction, comprising a fixed member or lug 48 and a longitudinally-movable arm or member 48^a, said movable member being adapted to approach and recede from the fixed member or lug 48 for a purpose 80 hereinafter explained. Arranged in the path of this actuator is an ear 49 at the front end of a traction-plate 50, and this traction-plate, which is shown in detail in Fig. 15, is mounted to slide longitudinally in the fore-stock and 85 is connected at its rear end by means of a link 51 with the lower long arm of the cocking-lever 44, whereby as the traction-plate is drawn forward the lower extremity of said lever is correspondingly moved to simultaneously throw the hammers back to an operative position. Also carried by the traction-bar 50 and arranged in the path of the rearward movement of said depending actuator on the barrel is an ear or stop 52, whereby as 95 the barrel is returned to its normal or closed position the traction-plate is correspondingly moved to throw the cocking-lever to the position indicated in Fig. 2, with its upper arm out of the path of the cocking-pins 43. Thus 100 when the barrel is released by the described movement of the draw or trip plate and is moved forward it first exposes the shells and then causes contact of the draw-plate actuator with the forward ear or stop 49 to carry 105 the traction-plate forward and cock the hammers, and after the removal and replacement of the cartridges the return of the barrel to its normal position is accompanied by the movement of the traction-plate due to the 110 contact of the actuator with the ear or stop 52 to throw the cocking-lever out of the path of the hammers, whereby either hammer may be actuated independently.

In order to provide for the detachment of 115 the barrel from the fore-stock, I have found it desirable to employ a sectional traction-bar having a hinged front member 53, which is adapted to swing downward from its horizontal position through an opening in the bottom 120 of the way provided for the guidance of the rib on the under side of the barrel, and thus adapt it to carry the forward ear or stop 49 downward out of the path of the forward movement of the traction-bar actuator to permit 125 said actuator to pass freely out through the end of the way. The said opening in the lower wall of the fore-stock is fitted with a hinged flap 54, also adapted when released to drop, and thus allow the hinged section of the traction-bar to be depressed; said hinged flap being normally held in position to close the opening in the fore-stock by means of a catch-bolt 130 55, mounted upon the fore-stock and provided

with an actuating-spring 56. The depressed position of the hinged flap is indicated in dotted lines in Fig. 2, and it is obvious that by drawing the traction-bar forward to bring 5 the hinge of its movable section in the plane or in advance of the hinge of said flap said section will also drop to withdraw the ear or stop 49 from the path of the actuator on the barrel.

10 Attached to the movable member 48^a of the traction-bar actuator, which is adapted to come into contact with the forward ear or stop 49 slightly in advance of the main or fixed portion of said actuator, is the stem 57 of a 15 cartridge-starter 58, which is let into a cut-away portion or cavity in the rear end of the barrel and is provided with segmental rim-seat sections 59, adapted for registration with the rim-seats 60, encircling the chambers of 20 the barrel at their rear ends to receive the rim 61 of a cartridge-shell 62. Hence with the cartridge-starter in its normal position (indicated in Fig. 2) the forward movement of the barrel to the position indicated in Fig. 25 5 will cause the contact of the movable actuator member 48^a with the forward ear or stop 49 of the traction-bar, and hence will cause the starter 58 to be moved rearwardly with relation to the barrel and draw any cartridges 30 which are in engagement therewith sufficiently to allow the operator to grasp and remove the same without inconvenience or danger. The special function of this cartridge-starter is to cause the rearward projection 35 from the barrel of cartridges which have not been exploded, and hence have not been engaged by the shell-extracting mechanism, hereinafter described, but which it may be desirable to remove from the barrel as preparatory to disconnecting the same from the 40 stock. The longitudinal slot 23 in the unlocking-slide 22 allows the movement of the traction-bar actuator, comprising the depending lug 48 and the movable arm or member 48^a, and its contact with the rear ear or stop 50 52 without affecting the position of said slide.

In connection with the above-described mechanism I employ a combination firing-pin and shell-extractor, whereby the operation of 55 advancing the firing-pin by means of the hammer to explode a cartridge serves to throw an extracting and ejecting arm into operative engagement with the rim of the shell thus exploded, whereby during the forward movement of the barrel to expose the rear end thereof said exploded shell is withdrawn 60 from the barrel and is finally ejected in a direction transverse to the length of the barrel. In the construction illustrated in the drawings, 65 63 represents a firing-pin reduced at its front end, as shown at 64, and headed or enlarged at its rear end, as shown at 65, the body portion of said pin being fitted for axial sliding movement in a tubular guide 66, having a downward extension 67, to which is attached an extracting and ejecting arm 68. Said arm projects forward from the down-

ward extension 67 of the guide 66 and is transversely yielding or resilient, with its front end provided with a shouldered and tapered 70 rim-engaging head 69. The firing-pin has a limited longitudinal movement in the guide 66, its forward movement independently of the guide being limited by the contact of the head 69 with the rear end of said guide, whereby when the headed rear end of the firing-pin receives the impact of the hammer it advances a short distance before imparting movement to the extractor and then carries the extractor forward with it to cause the projection of the shouldered head 69 of said extractor through an opening 70 in the breech-block in such a position as to engage the rim of the shell which has been exploded. The barrel is cut away at its under side to form a 85 bevel-walled cavity 71, into which this head of the extracting-arm projects when advanced; but the opening 70 in the breech-block through which the head 69 is advanced to engage the rim of the cartridge is of sufficient width to 90 allow transverse yielding of the extracting-arm, (preferably in a vertical plane,) and as the engagement of the head 69 with the shell-rim is accompanied by the transverse deflection or pressure of said extracting-arm it will 95 be seen that after the firing of the cartridge the extracting-arm exerts a transverse pressure upon the cartridge-rim not only sufficient to insure the operative engagement of the head 69 with the shell, but also sufficient, 100 if otherwise released, to eject the shell transversely from its position in alignment with the firing-pin. Obviously this transverse displacement of the shell is prevented while the parts of the gun are in their normal positions by the barrel-chamber in which the shell is fitted, as shown in Fig. 3. Also arranged upon the breech-block in operative relation with the shell-rim is a shell-deflecting pin 72, of which the projecting front end 105 is arranged approximately diametrically opposite to the extractor-head 69 and is beveled to form a deflecting-face 73, inclined downwardly and rearwardly and also slightly laterally, as clearly shown in Fig. 10. Thus 110 when a hammer is released to advance a firing-pin and discharge a cartridge the extractor is advanced to cause the engagement of the shouldered head 69 thereof with the rim of the shell. As the barrel is drawn forward, however, as shown in Fig. 4, the first portion of its movement does not affect the 115 position of the shell, which remains with its rim firmly in contact with the breech-block by reason of the engagement of the extractor-arm 68 therewith, said extractor-arm, however, being under tension and causing an upward pressure of the shell or rim against the deflecting-pin 72. As the advance of the barrel proceeds still further the movable member 120 48^a of the lug depending from the barrel comes in contact with the forward ear or stop 49 of the traction-bar and causes the advance 125 of the starter 58 to move the cartridge in the 130

other chamber of the barrel into a position where it may be grasped by the operator, as shown in Fig. 5, (it being understood that the engagement of a shell by the extractor is accomplished only by the firing of the cartridge, the unfired cartridge being wholly independent of the extractor, and hence being carried forward by the barrel, as shown.) When the advance of the barrel has proceeded sufficiently to liberate the front end of the shell, and thus remove the means whereby the shell was held in alignment with the firing-pin, the transverse resilience of the extractor-arm 68 will force the shell upwardly, the same being deflected by the face 73 of the deflecting-pin 72, and this transverse impulse imparted to the shell will be sufficient to throw the latter wholly out of the gun, the last step in the operation of ejecting the shell being indicated in Fig. 6.

Thus from the foregoing description it will be seen that if it is desired to open the breech end of a gun constructed in accordance with my invention preparatory to ejecting either of the cartridges it may be accomplished by simply moving the draw-plate or trip-plate rearwardly, such operation being adapted to be accomplished without removing the gun-stock from the shoulder, and when it is desired, after discharging one or both cartridges, to reload the movement of the barrel may be accomplished as above indicated, such operation being accompanied not only by the ejection of the exploded shell or shells, but the cocking of the hammers ready for immediate operation when the barrel is returned to close the breech, the locking of the barrel in its operative position being accomplished automatically. I have found it desirable, however, in practice to provide a trigger-locking or safety device whereby the triggers may be secured against operation while the hammers are in their cocked positions, and in the construction illustrated such safety device consists of a plate 74, mounted to slide upon the trigger-plate and adapted to occupy a position under the front ends of the triggers, said triggers being extended forwardly of their fulcrum-pins to form toes 75, which are depressed as the triggers are moved in opposition to their actuating-springs 41. This plate when moved to occupy a position under the toes 75 serves to prevent the depression of the latter, and thus locks the triggers, and the plate is movably held in either of its adjusted positions against displacement by jarring or otherwise by means of a spring 76, of which the nose engages one of a plurality of depressions 77, formed in the inner surface of the plate, as shown clearly in Figs. 2 and 11. Also the trigger-locking plate 74 is secured to the lug of a slide 78, located exteriorly of the draw-plate 28 and having its upper side channelled to receive said draw-plate, the end portions of the slide 78 being offset to embrace the side edges of the draw-plate, and thus serve to guide the same in its movement longitudi-

nally thereof. Also said offset end portions of the slide 78 are milled and project a short distance beyond the side edges of the draw-plate to adapt them to be engaged by the trigger-finger prior to firing the gun in order that the adjustment of the trigger-lock may be accomplished by means of the trigger-finger without loss of time in the firing of the piece. The slide is provided with a longitudinal slot 79, in which is pivoted a catch 80, having an oppositely-shouldered ear 81 and a projecting finger-piece 82, said shouldered ear projecting inwardly from the catch to occupy a position in a longitudinal slot 83 of the draw-plate for engagement by a stop or lug 84, carried by the draw-plate and obstructing said slot 83, said ear 81 being adapted to be arranged either in front or in rear of said stop 84 to adapt the draw-plate to communicate motion to the trigger-lock. The stop 84 is so located with relation to the other parts of the mechanism that when the ear 81 is arranged in rear thereof the rearward movement of the draw-plate to release the gun-barrel will move the plate 74 into position to engage and lock the triggers, whereas when the draw-plate is returned to its normal position motion is not communicated thereby to the trigger-lock, and hence said lock is allowed to remain in engagement with the triggers. On the other hand, when the ear 81 of the catch is arranged in front of the stop 84 the trigger-lock is permanently secured out of engagement with the triggers when the locking of the latter is not desired. The means illustrated for maintaining the catch 80 in either of its adjusted positions or, in other words, in engagement with the stop 84 at either side thereof consists of a turn-button 85, pivotally mounted upon the slide 78 and adapted to swing over the shank of the catch and lock the latter in the slot 79.

A further advantage of the construction described resides in the fact that the barrel may be released and moved forward sufficiently to allow the insertion of the cartridges into the barrel without cocking the hammers, after which the barrel may be returned to its normal position. Thus the piece may be carried in safety or without risk of premature discharge, and when it is desired to fire the same it is only necessary to release the barrel, slide it forward sufficiently to cock the hammers, and then return it to its normal position. Also the hammers may be let down after the loading and cocking thereof by releasing and sliding the barrel forward, drawing both triggers to cause the movement of the hammers to their "down" position, and then returning the barrel without jar to its normal position.

While the preferred embodiment of my invention is illustrated in the drawings and has been specifically set forth in the description, it will be understood that the essential features of construction are capable of various modifications and that numerous changes in the form, proportion, and minor details may

be resorted to without departing from the spirit or sacrificing any of the advantages of this invention.

Having described my invention, what I claim is—

1. In a firearm, the combination of a sliding barrel, a longitudinal rib at the lower side of the barrel comprising an upper dovetailed portion and a lower straight parallel-sided portion, the front portion of the frame of the firearm having a longitudinal channel formed with parts corresponding with the elementary parts of the longitudinal rib so as to hold the barrel in place and direct it in its reciprocatory movements, and means for locking the barrel when in a firing position, substantially as set forth.
2. In a firearm, the combination of a sliding barrel, a longitudinal rib at the lower side of the barrel having a dovetailed portion, the frame having its front portion longitudinally channeled and having a matching part corresponding with the dovetailed portion of the longitudinal rib, and an interlocking catch between the said rib and frame for securing the barrel in a normal position, substantially as set forth.
3. In a firearm, the combination of a sliding barrel, a longitudinal rib at the lower side of the barrel, the front part of the frame having a longitudinal channel to receive the said longitudinal rib and interlock therewith to hold and direct the barrel in its reciprocatory movements, and locking means applied to the said frame and normally projecting across the path of the aforesaid longitudinal rib to make positive and direct engagement therewith to secure the barrel in a normal position, substantially as specified.
4. In a firearm, the combination of a sliding barrel, an interlocking rib between the barrel and the front portion of the frame for holding the barrel in place and directing it in its reciprocatory movements, and a pair of oppositely-disposed catches to engage with the interlocking rib and hold the barrel in a normal position, with an unlocking-plate for releasing the catches, whereby the barrel is liberated, substantially as and for the purpose set forth.
5. In a firearm, the combination with a sliding barrel mounted upon the front portion of the frame of the firearm, of loosely-movable catches for engaging and securing the barrel in its operative position, an unlocking-slide having cam engagement with said barrel-locking catches and mounted for movement in a path parallel to the travel of the sliding barrel, and a draw-plate mounted on the frame adjacent to the trigger mechanism and independent of the latter, said draw-plate having an exposed finger-piece and connected with the unlocking-slide, substantially as described.
6. In a firearm, the combination with a sliding barrel mounted upon the front portion of the frame of the firearm, of independent lat-

erally-operating and vertically-operating catches for locking said barrel in its operative position, and a single unlocking-slide in operative engagement with said barrel-locking catches to retract both catches from the barrel, substantially as described.

7. In a firearm, the combination with a sliding barrel mounted upon the front portion of the frame of the firearm, of a plurality of catches for locking the barrel in its closed operative position, an unlocking-slide in operative relation to said catches, and movable operative means for actuating said unlocking-slide, substantially as described.

8. In a firearm, the combination of a sliding barrel, an interlocking rib between the barrel and that part of the frame upon which the barrel is slidingly mounted, and spring-actuated catches supported by the frame and having beveled ends and adapted to engage with the aforesaid interlocking rib and hold the barrel in a normal position, with an unlocking-plate having inclined portions to engage with the said catches for withdrawing them from engagement with the interlocking rib, substantially as set forth for the purpose described.

9. In a firearm, the combination of a sliding barrel, an interlocking rib between the barrel and frame upon which the barrel is slidingly mounted, spring-actuated catches normally projecting across the path of the interlocking rib to make positive engagement therewith and hold the barrel in a normal position, and having their inner lower portions cut away forming inclined shouldered portions, and an unlocking-bar supported beneath and in engagement with the lower side of the aforesaid interlocking rib and having inclined portions to engage with the inclined shouldered parts of the catches for withdrawing the latter from engagement with the interlocking rib, substantially as specified.

10. In a firearm, the combination of a sliding barrel, an interlocking rib between the barrel and the frame upon which the barrel is slidingly mounted, and catches supported by the frame and adapted to engage with the interlocking rib, and having their inner ends beveled and formed with correspondingly-inclined shoulders, with an unlocking-plate having oppositely-disposed triangular-shaped notches forming inclined edge portions to engage with the inclined shoulders of the catches, substantially as described for the purpose specified.

11. In a firearm, the combination of a breech-block, a sliding barrel having a rearwardly-extending lug arranged, in the closed position of the barrel, to overlap said breech-block, a transversely-movable locking-bolt mounted on the breech-block to engage with said lug and lock the barrel, an unlocking-slide having operative connection with the locking-bolt, and means for actuating said unlocking-slide, substantially as described.

12. In a firearm, the combination of a breech-

- block having a vertical opening, a barrel having a rearwardly-extending lug about in the plane of its top portion to overlap the breech-block and notched in its lower side, a locking-bolt mounted in the aforesaid vertical opening in the breech-block to engage with the notched portion of the lug for holding the barrel in place, a lever having loose connection with the locking-bolt, a sliding plate, and means connecting the lever with the plate, substantially as described for the purpose specified.
13. In a firearm, the combination of the barrel having a rear lug and slidably mounted upon the frame, a locking-bolt mounted in an opening of the breech-block to engage with the said lug, and a lever having loose connection with the locking-bolt, with locking means between the barrel and the frame, and an unlocking-plate for releasing the said locking means and adapted to operate the aforesaid lever for withdrawing the locking-bolt, substantially as set forth.
14. In a firearm, the combination of a locking mechanism between the barrel and the frame upon which the barrel is slidably mounted, and an unlocking-plate for releasing the said locking mechanism, with a locking-bolt engaging a rear extension of the barrel, and a lever having connection with the locking-bolt and projecting across the path of the unlocking-plate to be operated by the latter and having a limited movement independently thereof, substantially as specified.
15. In a firearm, the combination with a barrel slidably mounted on a frame, of a series of locking devices for retaining the barrel in firing position, an unlocking-slide in operative relation to said locking devices for simultaneously releasing the same, and a draw-plate connected with said unlocking-slide, substantially as described.
16. In a firearm, the combination with a barrel slidably mounted on a frame, and locking mechanism for holding the barrel in firing position, of a slotted unlocking-plate slidable with relation to the locking mechanism, and a draw-plate slidably confined on the frame and having at one end a finger which engages the slotted unlocking-plate and provided at its other end with a finger-piece arranged in rear of a trigger-guard, substantially as described.
17. In a firearm, the combination with a barrel slidingly mounted upon the frame and having a projection, and the gun-lock having a hammer, of a lever adapted to engage the hammer for cocking the same, and a traction-bar having connection with the lever and provided with spaced stops arranged respectively in front and in rear of said projection on the barrel, substantially as specified.
18. In a firearm, the combination with the barrel slidably mounted upon the frame and having a pendent portion, and the gun-lock, of a pivoted lever adapted to engage with a portion of the hammer, and a traction-bar having connection with the pivoted lever and

adapted to be operated by the pendent portion of the barrel for cocking the gun simultaneously with the forward movement of the barrel, substantially as set forth.

19. In a firearm, the combination with the barrel slidably mounted upon the frame and having a pendent portion, and the gun-lock, of a pivoted lever for cocking the hammer, a traction-bar operated by the pendent portion of the barrel when moving the latter forward, and a link connecting the pivoted lever with the traction-bar, substantially as specified.

20. In a firearm, the combination of a barrel slidably mounted upon the frame and having a pendent portion, the gun-lock, a pivoted lever extending into the path of a portion of the hammer, a traction-bar having connection with the pivoted lever, and lugs projecting from the traction-bar to be engaged by the pendent portion of the barrel, whereby the traction-bar is positively actuated in each direction when sliding the barrel, substantially as specified.

21. In a firearm, the combination of a double barrel slidably mounted upon the frame, a gun-lock for each barrel, a single lever in the path of which are arranged projections on the hammers of both locks, and means actuated by the barrel for moving the lever to simultaneously cock both gun-locks upon sliding the barrel forward, substantially as specified.

22. In a firearm, the combination of a double barrel slidably mounted upon the frame, a gun-lock for each barrel, the hammer of each gun-lock having a projection, a pivoted lever, in the path of which the said projections of both hammers are arranged, and a traction-bar, actuated by the barrel, for operating said lever, substantially as specified.

23. In a firearm, the combination of a double barrel slidably mounted upon the frame, a gun-lock for each barrel, the hammers of the gun-locks having inwardly-extending projections, a pivoted lever intermediate of the gun-locks and in the path of both projections of the hammers for simultaneously cocking them, and a traction-bar having connection with the pivoted lever and adapted to be operated when sliding the barrel forward for simultaneously cocking both gun-locks, substantially as specified.

24. In a firearm, the combination with a barrel slidingly mounted upon the frame, and the gun-lock having a hammer, of a hammer-cocking lever fulcrumed coaxially with the hammer for engagement therewith, and means for communicating motion from the barrel to said cocking-lever, substantially as specified.

25. In a firearm, the combination with a barrel slidingly mounted upon the frame, and the gun-lock having a hammer provided with a lateral pin, of a hammer-cocking lever fulcrumed coaxially with the hammer for engagement with said pin which is arranged in the path of the lever when the latter is moved in one direction, and means for communicating

ing motion from the barrel to said lever, substantially as specified.

26. In a firearm, the combination with a barrel slidingly mounted upon the frame, and the gun-lock having a hammer, of a traction-bar operatively connected with the hammer, and having a transversely-displaceable lug normally arranged in the path of a projection on the barrel, and adapted by transverse placement to be removed from the path thereof, substantially as specified.

27. In a firearm, the combination with a barrel slidingly mounted upon the frame, and the gun-lock having a hammer, of a traction-bar operatively connected with the hammer, and having a hinged transversely-movable section carrying a lug which is normally arranged in the path of a projection on the gun-barrel, substantially as specified.

28. In a firearm, the combination with a barrel slidingly mounted upon the frame, and the gun-lock having a hammer, of a traction-bar operatively connected with the hammer and having a depressible section carrying a lug in the path of a projection on the gun-barrel, and movable means for holding the lug-carrying section in its normal position, substantially as specified.

29. In a firearm, the combination with a barrel slidingly mounted upon the frame, and the gun-lock having a hammer, of a traction-bar operatively connected with the hammer and having a depressible section carrying a lug in the path of a projection on the gun-barrel, and movable downwardly through an opening in the fore-stock, and a movable flap for normally closing the opening of the fore-stock and supporting the lug-carrying section of the traction-bar, substantially as specified.

30. In a firearm, the combination with a slideable barrel, and a gun-lock having a hammer, of a traction-bar operable by the slideable movement of the barrel and having operative connection with the hammer, said traction-bar having a section depressible out of the path of the barrel and through an opening in the fore-stock, and means for closing said opening, substantially as described.

31. In a firearm, the combination with a slideable barrel, and a gun-lock having a hammer, of a traction-bar connected operatively with said hammer and provided with a movable section adapted to be shifted out of the path of the traction-bar-actuating means on the barrel previous to dismounting the latter, said movable section of the traction-bar being adjustable through an opening in the fore-stock, a flap for closing said opening, and a catch to confine the flap in its closed position, substantially as described.

32. In a firearm, the combination with the barrel slidingly mounted upon the frame and having a pendent portion, of a firing mechanism, and a traction-bar for cocking the firing mechanism and having an upward extension at its front end, and hinged at an interval in rear of its front end, and a rear pro-

jection in the path of the aforesaid pendent portion of the barrel, and in rear of the hinge, whereby the traction-bar is positively actuated in both directions, substantially as and for the purpose specified.

33. In a firearm, the combination with a barrel movable independently of a breech-block, of a slideable shell-ejector constructed to embrace the rim of the cartridge-shell and with its rim-engaging portion normally out of engagement with the rim, as set forth.

34. In a firearm, the combination with a barrel, movable independently of a breech-block, of a shell-ejector having a rim-engaging portion movable to a point in front of a cartridge-rim shell and normally confined in rear of and free from engagement with said cartridge-rim, as set forth.

35. In a firearm, the combination with a barrel movable independently of the breech-block, of a rim-engaging ejector movable in a plane parallel with the path of the barrel, said movable ejector being resilient in a direction transversely of the barrel, substantially as described.

36. In a firearm, the combination with a barrel movable independently of a breech-block, of an ejector having a rim-engaging portion normally in rear of the position occupied by a cartridge-rim in said barrel, said ejector being bodily movable in a direction to advance said rim-engaging portion into engagement with a cartridge-rim, and said ejector being also resilient transversely to eject a shell engaged by said rim-engaging portion, as set forth.

37. In a firearm, the combination with a barrel and a breech, one movable with relation to the other, of a rim-engaging cartridge-extractor normally out of engagement with the cartridge, and a firing mechanism to engage said extractor with the cartridge, substantially as described.

38. In a firearm, the combination with a barrel, longitudinally movable independently of the breech-block, of a transversely-resilient ejector for engaging the rim of a cartridge, and exerting transverse ejecting pressure thereon, and projections in the path of the rim of the cartridge to oppose the pressure of the ejector until the cartridge is released from the barrel, substantially as specified.

39. In a firearm, the combination with a barrel, longitudinally movable independently of the breech-block, of a transversely-resilient ejector for engaging the rim of a cartridge and exerting transverse ejecting pressure thereon, and a beveled deflecting-face arranged in the transverse path of, for engagement with, the cartridge-rim at a point opposite to said ejector, to oppose the transverse displacement of the rim until the barrel reaches a predetermined point, substantially as specified.

40. In a firearm, the combination with a barrel, longitudinally movable independently of the breech-block, of a transversely-resilient ejector for engaging the rim of a cartridge, and

a forwardly and laterally beveled projection in the path of the cartridge-rim, to oppose the transverse displacement of the rim under the pressure of the ejector until the barrel reaches 5 a predetermined point, substantially as specified.

41. In a firearm, the combination with a longitudinally-movable barrel, and a lock having a hammer, of a hammer-actuated cartridge-extractor, having a rim-engaging portion normally arranged in rear of the cartridge-rim, and movable by the hammer to a point in front thereof, substantially as specified. 70

42. In a firearm, the combination with a longitudinally-movable barrel, and a lock having a hammer, of transversely-resilient hammer-actuated cartridge-extractor, having a bevel-faced rim-engaging head normally arranged in rear of the cartridge-rim and movable by the hammer to a point in front thereof, substantially as specified. 75

43. In a firearm, the combination of a breech-block having recesses in its rear end and lower side, the side recess communicating at its front end with the rear portion of the bore, and a firing-pin located in the rear recess, with an ejector arranged in the side recess and connected with the firing-pin so as to move therewith, substantially as set forth. 80

44. In a firearm, the combination of a breech-block having recesses in its rear end and lower side, the side recess communicating at its front end with the rear portion of the bore, a firing-pin located in the rear recess, and a lug carried by the firing-pin and extending into the rear portion of the side recess, with a spring-ejector arranged in the side recess and rigidly connected with said lug to move with the firing-pin, substantially as and for the purpose specified. 85

45. In a firearm, the combination of a breech-block having recesses in its rear end and lower side, and the side recess communicating at its front end with the rear portion of the bore, and the barrel having a side recess in communication with the bore, and provided with a cam-faced wall, of an ejector located in the recess of the breech-block, and adapted for forward movement to enter said side recess of the barrel to engage the rim of a cartridge, substantially as specified. 90

46. In a firearm, the combination with a barrel and gun-lock, of a firing-pin, a cartridge-extractor having a rim-engaging portion normally arranged in rear of the cartridge-rim, and means for communicating motion from the firing-pin to the extractor, substantially as specified. 95

47. In a firearm, the combination with a barrel and gun-lock, of an extractor, normally arranged with its shell-engaging portion in rear of the rim of a cartridge arranged in the barrel, and adapted for actuation by the firing mechanism to engage a cartridge-rim, substantially as specified. 100

48. In a firearm, the combination with a bar-

rel and gun-lock, of a firing-pin, and a cartridge-extractor, arranged in the path of a portion of the firing-pin, and having a rim-engaging portion normally arranged in rear of the cartridge-rim, and adapted for movement to a point in front thereof, said firing-pin having a limited movement independently of the cartridge-extractor, substantially as specified. 105

49. In a firearm, the combination with a barrel and gun-lock, of a firing-pin and an armed extractor, connected therewith for simultaneous actuation by the hammer of the gun-lock, and having a limited movement independent of each other, substantially as specified. 110

50. In a firearm, the combination with a barrel and gun-lock, of a reciprocatory extractor to engage a shell, and having a longitudinal guide, and a firing-pin mounted in said guide and adapted to communicate motion to the extractor, substantially as specified. 115

51. In a firearm, the combination with a movable barrel, a locking mechanism therefor, and a firing mechanism adapted to be set by movement of the barrel, of a draw-plate connected with said locking mechanism to release the latter from the barrel, and a trigger-locking device movable with said draw-plate into engagement with the trigger on the release of the locking mechanism by the draw-plate, said trigger-locking device being shiftable on the draw-plate out of operative relation to the triggers and adapted to remain at rest independently of the movement of the draw-plate, substantially as described. 120

52. In a firearm, the combination with a movable barrel, a locking mechanism for said barrel and firing mechanism including a trigger, of a draw-plate having operative connection with the barrel-locking mechanism, and a trigger-locking device provided with a slide and adapted to be actuated by said draw-plate, said slide of the trigger-locking device being movable with the draw-plate for adjustment into engagement with the trigger on the movement of the draw-plate to release the barrel-locking device, and said slide and trigger also shiftable on the draw-plate out of the path of the trigger, substantially as described. 125

53. In a firearm, the combination with a movable barrel, locking mechanism for said barrel including a draw-plate, and firing mechanism including a trigger, of a trigger-locking device carried by the draw-plate of said firing mechanism to be movable therewith and also shiftable to various positions on said draw-plate, whereby in one position of the trigger-lock it will be engaged and disengaged automatically with the trigger as the draw-plate is moved and in another position of the trigger-lock it is wholly disconnected from the trigger on the movement of the draw-plate, substantially as described. 130

54. In a firearm, the combination with a barrel-locking mechanism, and a trigger, of means for releasing the barrel-locking mechanism,

and a trigger-lock carried by an element of the device for releasing the barrel-locking mechanism and movable automatically into and out of engagement with said trigger, said 5 trigger-lock being also shiftable relatively to the means for releasing the barrel-locking mechanism and under such conditions free from the trigger on the travel of the element which releases the barrel-locking mechanism, 10 substantially as described.

55. In a firearm, the combination with a movable barrel, locking mechanism for the barrel, a trip-plate connected operatively with the barrel for actuation thereby, and firing mechanism, including a trigger, of a trigger-locking device, and adjustable means for connecting the same with said trip-plate, for actuation when the barrel is released, substantially as specified.

56. In a firearm, the combination with a movable barrel, locking mechanism for the barrel, a trip-plate, and firing mechanism, including a trigger, of a trigger-locking device, and a movable catch for throwing the same 25 into and out of operative relation with the said trip-plate, substantially as specified.

57. In a firearm, the combination with the firing mechanism, and a safety device for securing the firing mechanism against accidental 30 movement, of a pivoted catch having connection with the safety device to be thrown into and out of action, and a draw-plate for engagement with the catch when thrown into an operative position and automatically securing the firing mechanism, substantially as 35 set forth.

58. In a firearm, the combination with the firing mechanism, and a safety device therefor, of a catch adapted to be thrown into and 40 out of an operative relation with the safety device, means for holding the catch in operative position, and a draw-plate for automatically engaging with the catch and moving the safety device into position for securing the firing mechanism against accidental movement, 45 substantially as set forth.

59. In a firearm, the combination of a movable breech-loading barrel, a locking mechanism for securing the barrel in a normal position, a firing mechanism, a safety device for the firing mechanism, and a catch applied to the safety device to be thrown into and out of engagement with the locking mechanism, with a draw-plate for releasing the locking 55 mechanism and engaging with the said catch to set the safety device, substantially as and for the purpose set forth.

60. In a firearm, the combination with the firing mechanism, of a lock-plate to be projected across a portion of the trigger, a slide connected with the lock-plate, a catch pivoted to the slide and having a stop, a turn-button applied to the slide for holding the catch in working position, and a draw-plate adapted 65 to engage with the stop of the catch to move the lock-plate into engagement with the trigger, substantially as specified.

61. In a firearm, the combination of a movable barrel, locking mechanism therefor, a stationary trigger plate and guard, a draw-plate mounted slidably on the trigger-plate to extend in rear of the trigger-guard and a releasing-plate connecting the draw-plate with said locking mechanism to release the barrel, said draw-plate provided with the spaced grip-ears, both located outside and in rear of the trigger-guard, substantially as described.

62. In a firearm, the combination of a movable barrel, locking mechanism therefor, a trigger plate and guard, a slide draw-plate 80 mounted on the trigger-plate to extend in rear of the trigger-guard and provided with an exposed grip-ear in rear of the trigger-guard and with a follower, means connecting the draw-plate with the barrel-locking mechanism and 85 a return-spring supported by the trigger-plate in engagement with the follower on said draw-plate, substantially as described.

63. In a firearm, the combination with a 90 slidingly-mounted barrel, and hammer-cocking devices, including a traction-plate having a lug, of a depending projection supported by the barrel to engage said lug, the projection having a limited movement independently of and parallel with the barrel, and a cartridge-starter connected to the projection, for extension when the projection comes in contact with said lug on the traction-bar, substantially as specified.

64. In a firearm, the combination with a 100 slidingly-mounted barrel, and hammer-cocking devices, including a traction-plate having front and rear spaced lugs, of a depending sectional actuator supported by the barrel, one member of the actuator being fixed and 105 the other movable with relation to the barrel, and said members being adapted for engagement respectively with said rear and front lugs of the traction-bar, for positively actuating the same, and a cartridge-starter, seated 110 in the rear end of the barrel, and connected with said movable member of the actuator, substantially as specified.

65. In a firearm, the combination with a 115 gun-lock and a barrel movable independently of a breech-block, of a reciprocatory firing-pin, and a shell-ejector movable a limited distance with said firing-pin and having a transversely-movable member for imparting movement to a shell when released by the barrel, 120 substantially as described.

66. In a firearm, the combination with a barrel, axially movable independently of the breech-block, of a shell-ejector having a transversely-movable element for actuating a shell 125 when released by the barrel, said element being normally located out of and being longitudinally movable into, engagement with a shell, substantially as specified.

67. In a firearm, the combination with a barrel, axially movable independently of the breech-block, of a shell-ejector having a transversely-movable element for actuating a shell 130 when released by the barrel, and a fixed de-

flector for throwing the rear end of the shell from the breech-block, substantially as specified.

68. In a firearm, the combination with a barrel, movable independently of the breech-block, of a firing-pin and a shell-engaging ejector connected together for simultaneous actuation, the former being rearwardly movable independently of the latter to release the shell for transverse displacement, substantially as specified.

69. In a firearm, the combination with a barrel, movable independently of the breech-block, of a firing-pin and a shell-engaging ejector connected together for simultaneous actuation, the former being rearwardly movable independently of the latter to release the shell for transverse displacement, and the latter being transversely movable independently of the former to eject the shell when released by the barrel, substantially as specified.

70. In a firearm, the combination with a barrel, movable independently of the breech-block, of connected cartridge-exploding and shell-rim-engaging members, the latter being transversely resilient for holding a shell during the forward movement of the barrel, and imparting transverse movement to the

shell when released by the barrel, substantially as specified.

71. In a firearm, the combination with a barrel, movable independent of the breech-block, of an ejector having a transversely-resilient element movable longitudinally of the breech-block for engaging and holding a shell during the forward movement of the barrel, and imparting transverse movement to the shell when released from the barrel, and means for communicating longitudinal movement to said ejector element from a movable member of the gun-lock, substantially as specified.

72. In a firearm, the combination with a barrel, movable independently of the breech-block, of an ejector having a transversely-resilient element for imparting transverse movement to a shell when released by the barrel, and a deflecting-pin, disposed in the path of transverse movement of the shell, for throwing the same forward from the breech-block, substantially as specified.

In testimony that I claim the foregoing as my own I have hereto affixed my signature in the presence of two witnesses.

CALEB S. EVANS.
